(57) **CLAIM**

The ornamental design for a decking panel, as shown and described.

DESCRIPTION

FIG. 1 is a perspective view from the front, top, and right side of the decking panel embodying our new design;
FIG. 2 is an end elevational view thereof, the other end elevational view being a mirror image thereof;
FIG. 3 is a right side elevational view thereof;
FIG. 4 is a left side elevational view thereof;
FIG. 5 is a top plan view thereof; and,
FIG. 6 is a bottom plan view thereof.

The double spaced parallel lines in the FIGS. 1, 3, 4, 5 and 6 are intended to indicate that the decking component is indefinite in length.
